UNITED STATES PATENT OFFICE.

HUGH ARTHUR THOMSON, OF GLASGOW, SCOTLAND, ASSIGNOR TO SCIENTIFIC TREATMENTS LIMITED, OF GLASGOW, SCOTLAND.

OZONE-PRODUCER.

1,105,717.

Specification of Letters Patent.

Patented Aug. 4, 1914.

Application filed August 5, 1912. Serial No. 713,276.

To all whom it may concern:

Be it known that I, HUGH ARTHUR THOMSON, electrical engineer, of 81 West Regent street, in the city of Glasgow, Scotland, have invented certain new and useful Improved Ozone-Producers, of which the following is a specification.

My invention relates to that class of apparatus for the production of ozone from atmospheric air by a silent discharge of high potential electricity obtained either from a supply company's main or from a rotary converter driven off the supply company's main, say at 250V direct current or otherwise and giving off a lower voltage in alternating current, which is then passed into the primary side of a step-up transformer from which the desired higher voltage is obtained through the secondary. This high potential current is then conveyed to a number of condenser tubes hereinafter described.

In apparatus for the production of ozone a series of open ended cylindrical glass tubes have been employed, each tube being fitted with an external and an internal wire gauze or meshed wirework electrode and arranged in a stack, all the external electrodes being in contact and all the tubes being parallel, the stack being held together by a wooden framework and the whole being placed in a box or casing having an air inlet and outlet; and a series of open ended cylindrical glass tubes each fitted with an external electrode of sheet-metal having punched out tongues and an internal electrode of wire gauze have been held apart and parallel with one another in a framework arranged in a box or casing having at one end a number of holes to admit air and at the other end an air outlet; and it has also been proposed to regulate the quantity of ozone produced by an ozonizing apparatus by connecting the terminals of the electrodes to a series of contacts over which a curved contact piece is adapted to move so as to place in circuit the desired number of electrodes.

According to my invention, the electrodes, which are made of Hollander wire cloth, are placed, one inside and one outside of a glass cylinder or tube of any suitable diameter. This Hollander wire cloth has usually 60x10 meshes to the inch differing from ordinary wire gauze which is usually of equal meshes to the inch. The use of this Hollander wire cloth allows a freer passage of air between

the cloth and tube and thereby preventing a rise in temperature which would result in oxids of nitrogen being formed. The tube being of cylindrical formation there is no liability to short circuiting between the opposite polarities. The above condenser tubes which may be of any number are supported by a board of teak wood or other suitable material, at each end of the tubes by means of holes bored to suit and lined with felt to allow of any expansion of the glass. The teak wood boards supporting condensers have holes bored in spaces between the tubes which allow of a free passage of air through the inside and around outside of tubes. By this arrangement the passage for air is so complete that the electrodes are continually kept cool and the possibility of oxids of nitrogen forming is reduced to a minimum. The ozone produced by this means described generally above is then passed into an extended chamber having a cone-shaped inlet and a similar outlet.

The invention is clearly set forth by reference to the accompanying drawings forming part of this specification, which are described as follows:

Figure 1 shows in elevation the apparatus herein described, in side and end views. Fig. 2 is a plan. Fig. 3 is a cross section taken substantially on the line A—B, Fig. 2. Fig. 4 is a similar view taken on the line C—D, Fig. 2.

As already explained, the alternating current may be obtained from a district supply company's mains, in which case there is no necessity for a rotary converter being employed, but if the district supply be a direct current supply the same is then passed into a rotary converter and transformed to alternating. There is also the possibility of my making use of a storage battery supply, but all these modes of production are equally common property. This supply of alternating current at a suitable periodicity in cycles is passed into a step-up transformer at the primary terminals and gives off a charge of high potential at the secondary terminals. The said transformer is marked 17. From one E of the two terminals on the primary side of the step-up transformer a connection 24 is carried to ammeter 18, from thence a wire connection 23 is carried to a plug terminal 20. This plug takes the alternating current from the rotary converter into appa-

ratus by connection 22. From the other terminal F of transformer 17 a connection 25 is carried to the same plug thereby completing the circuit.

5 I have provided a means of cutting in or out of action from one to any number of condenser tubes which makes the one machine or apparatus suitable for many different purposes, according to the quantity of ozone 10 required.

The above arrangement is carried out as follows: A connection 26 is carried from one E¹ of the secondary terminals of transformer 17 and joined by means of a coupling 21, to each and all of the wires from the inner Hollander wire cloths of the condenser tubes in the ozone producing chamber 2. From the other F¹ of the secondary terminals of the transformer 17, a connection 27 is carried to and connected with the center of a controller 19. The part of this controller to which this connection is connected takes the form of a half circular knife blade which passes between laminated 15 contacts thereby cutting the plates into or out of action. From the outer Hollander wire cloth surrounding the glass condenser tube, a connection 28 is carried to each of the terminal laminated contacts on controller 19. It will be clearly seen that as the handle of controller is turned around, it cuts 20 out of action all or any number of the electrodes at will. No claim is made to this construction *per se*. The ozone thus produced, by the process above described, is 25 passed through a cone-shaped inlet 11 into an extended oxidizing chamber 3 and thence through a similar outlet 12.

The chamber 3 is provided for the purpose 30 of subjecting any suitable substance therein, such as an oil, drug, or the like, more particularly oils having certain healing properties in cases of bronchitis, asthma, phthisis, etc., to the oxidizing influence of 35 the ozone produced in the chamber 2, thereby providing for a suitable medication of the ozone delivered through the outlet 12.

The condenser tubes 8, 9 and 10 are supported at each end by means of a frame of 40 teak wood or other suitable material 6. This frame or board has holes 7 cut to suit the sizes of tubes, which vary according to 45 size of apparatus. These holes 7 are shown in Fig. 3 and are lined with felt to provide 50 easy resting places and room for expansion, if any, of tubes. The electrodes are composed of a glass cylinder or tube 8 preferably round, but may be of any shape and size, and the number used will vary accord-

ing to size of apparatus required. Inside 80 this tube or cylinder 8, a sheet of Hollander wire cloth 9 soldered so as to make it of the same shape as the glass cylinder or tube 8 and to fit tightly inside is placed with connection therefrom as previously described. 65 The teak wood, or other boards 6 are provided with holes or spaces 30 between the tubes to admit of a free passage through the inside and around outside of tubes.

On the outer surface of the glass cylinder 70 or tube 8 a similar piece of Hollander cloth 10 is placed and each of these outer conductors are connected as before described to one of each of the terminals of the controller. 4 is the inlet for the air supply 75 and any quantity of air may be drawn or forced by means of an electricity driven, or hand or belt driven blower, if desired, or otherwise.

The extended chamber 3 is separated by 80 means of a partition L of wood or the like from the ozone producing chamber 2 and the whole apparatus is inclosed in an outer case I, Figs. 3 and 4, and made of oak wood, or other suitable material. 85

In operation air passes through the inlet 4 into the generating chamber in which the ozone producer is located, and the oxygen thereof is converted into ozone which, passing through the cone shaped inlet 11 into the oxidizing chamber 3, oxidizes the medicaments in said oxidizing chamber, the resulting medicated gas being delivered at the cone shaped outlet 12. 90

Claim—

An apparatus for producing ozone from atmospheric air comprising a series of glass cylinders or tubes each provided internally and externally with an electrode of wire cloth, and affording a tubular passage for 100 air, thereby keeping the condenser cool and preventing the production of oxid of nitrogen, means for supplying a high potential current to said electrodes, and end members provided with holes or openings in which 105 said tubes are supported, said holes or openings being lined with felt to permit expansion of the glass, and said end members being provided with additional holes for passage of air around outside of said tubes to 110 keep the same cool, substantially as described.

In testimony whereof I affix my signature in presence of two witnesses.

HUGH ARTHUR THOMSON.
